DESIGN FOR A MANICURE SUPPLY HOLDER

Francis P. Sheridan, Woodland, Calif.

Application May 13, 1936, Serial No. 62,616

Term of patent 7 years

To all whom it may concern:

Be it known that I, Francis P. Sheridan, a citizen of the United States, residing at Woodland, in the county of Yolo and State of California, have invented a new, original, and ornamental Design for a Manicure Supply Holder, of which the following is a specification, reference being had to the accompanying drawing, forming a part thereof.

Fig. 1 is a top plan view of the manicure supply holder showing my new design.

Fig. 2 is a side elevation of the same.

Fig. 3 is a sectional elevation of the manicure supply holder, taken on line 3—3 of Fig. 1.

I claim:

The ornamental design for a manicure supply holder, as shown.

FRANCIS P. SHERIDAN.
